UNITED STATES PATENT OFFICE.

KARL WILLIAM HALLDEN, OF WATERBURY, CONNECTICUT.

SHEET-METAL CUTTING-OFF MACHINE.

Application filed May 22, 1920, Serial No. 383,441. Renewed October 25, 1922. Serial No. 596,912.

To all whom it may concern:

Be it known that I, KARL WILLIAM HALLDEN, a citizen of the United States, residing at Waterbury, in the county of New Haven 5 and State of Connecticut, have invented certain new and useful Improvements in Sheet-Metal Cutting-Off Machines, of which the following is a specification.

My invention relates to improvements in sheet metal cutting-off machines, and the object of my improvement is to produce a cutting-off machine for use in cutting off sheet metal in prescribed lengths that is automatic in operation, that operates to shear the metal 15 and is also provided with means for straightening the metal, and that is reliable and efficient in use, in that means are provided for obtaining substantial uniformity of length for a particular setting of the machine, and 20 that, furthermore, has means for obtaining a relatively large range for the lengths.

In the accompanying drawing:

Figure 1 is a side elevation of my improved sheet metal cutting-off machine.

Figure 2 is a plan view of the same.

Figure 3 is a rear elevation of the same.

Figure 4 is a view partly in front elevation and partly in section.

Figure 5 is a fragmentary side elevation 30 of the crank-disk, showing the adjusting key in position for use.

Figure 6 is a fragmentary elevational view, as viewed from the right side, or reverse side from Fig. 1, of the driving means 35 for the eccentric control device for the moving shear blade.

Figure 7 is a sectional view on the line 7—7 of Fig. 6.

Figure 8 is a fragmentary sectional view 40 of the rack and adjacent parts, (Sheet 3).

Figure 9 is a view part in section and part in side elevation of the one-way clutch for the driving mechanism.

Figure 10 is a fragmentary sectional view 45 of the same on the line 10—10 of Fig. 9.

Figure 11 is a fragmentary sectional view on the line 11—11 of Fig. 4, showing the plate for the moving cutter.

Figure 12 shows the feed roll shaft and 50 parts mounted thereon.

Figure 13 is a fragmentary view on an enlarged scale and in part broken away of certain parts shown in Fig. 11, showing one corner of the gate and the adjacent parts.

Figure 14 is a sectional view on the line 55 14—14 of Fig. 13.

My improved sheet metal cutting-off machine comprises a frame 10 that is appreciably elongated that supports adjacent the middle portion a pair of shearing cutter 60 blades comprising the lower fixed blade 11 and the upper moving blade 12 that is operatively supported for movement in a vertical plane, and has at the rear of the said blades feeding and straightening devices 65 comprising the pair of feed rolls 13 and 14 adjacent the said blades 11 and 12 and a set 15 of straightening rolls immediately to the rear of the said feed rolls 13 and 14, and is provided with mechanism, driven by the 70 motor 16, for intermittently feeding the stock to the cutter blades and effecting the cutting of the stock during the dwell or period of rest for the feeding devices.

The main shaft 17, positioned substantially so that its axis is in a common vertical plane with the middle of the plate or gate 18 that supports the moving cutter 12 and the shaft 19 that is operatively housed at the upper end portion of the said gate 18 and 80 serves as the connecting means for operatively connecting the said gate 18 with the said main shaft 17, through the medium of cam devices comprising two similar cams 20 that are mounted on the said main shaft 17, 85 in spaced relation, as shown in Fig. 4.

The fixed shear blade 11 is supported from the frame 10 in any desired manner and the opposed and cooperating cutting edges 21 of the two blades 11 and 12 may be slightly 90 inclined, as shown.

The upper moving blade 12 is secured to the gate 18 in any desired manner and the gate 18 is operatively housed in a guideway structure 22 of suitable form.

The gate operating mechanism is made of duplex form for positively driving each side of the gate and comprises, accordingly, on each side, a cam housing 23 for cooperating with the cam 20 and having an upward extension 24 that serves as the connecting means and is suitably threaded for adjustably receiving the lower end of the rod 25 that serves as the connecting rod and, as shown, is in the form of a stud.

At the upper end of the connecting rod-stud 25 is a bearing structure 26 in which is positioned a relatively short bearing portion 27 of the gate shaft 19.

The gate 18 is mounted on the portion 28 110 of the shaft 19 that is intermediate the two connecting rod bearing structures 26 by

means of a pair of bearing devices 29 that are provided at the upper end portion of the gate structure 18.

The cams 20 are eccentric cams and serve 5 through the connecting means described to impart a limited upward and downward movement to the gate 18 when the main shaft 17 is rotated.

The cams 20, mentioned, determine the 10 range of movement of the gate 18, such movement, with a suitable adjustment of the parts, serving to bring the cutting blades 21 into cooperation for effecting the cutting of the sheet metal.

15 I prefer to so construct the parts that notwithstanding such reciprocating movement as may be effected by the cams 20 the gate will be adapted to be shifted so as to be out of commission so far as concerns the feature of bringing the cutting edges 21 into 20 operation.

That is to say, the gate 18 may be shifted in its position relatively to the gate operating means that as the gate is moved downwardly the cutting edges 21 may or may not be brought into cooperation, depending upon the particular setting of the gate shifting means.

Thus, combined with the gate moving 30 means are other means that may be designated as gate shifting or gate setting means.

These latter means will now be described.

The essential feature thereof is the provision of the intermediate gate supporting 35 portion 28 of the gate shaft 19 in the form of an eccentric, relatively to the adjacent bearing portions 27 of the said gate shaft 19, as will be noted from an inspection of Figs. 3 and 4.

40 Thus, by rotating the gate shaft 19 the gate 18 will be raised or lowered relatively to the gate moving devices for changing the setting of the gate, the eccentricity of the intermediate shaft portion 28 being made such that when the gate is in the raised position the cutting edges 21 will not operate to cut sheet metal that may be interposed therebetween.

Such an arrangement permits of throwing 50 the cutters out of commission altogether if desired and also permits of being combined with other means, as shown and to be described, for increasing the range of the machine for the lengths of stock that can be cut automatically.

The gate 18 is positively guided and positioned vertically and serves to positively position the part 28 of the shaft 19 to which it is connected, and the side parts 27 when 60 changed in position are swung around relatively to the axis of the intermediate part 28 to change the vertical relation of the parts.

The limit for the stock to be cut would generally be about one-eighth of an inch in 65 thickness, so that I find it easily feasible to

provide sufficient eccentricity in the gate shaft 19 to provide for shifting the relation of the gate 18 and the connecting rods 25 between the two extreme positions, one for effecting the cutting of the stock and the other 70 for avoiding such cutting.

In order to permit of turning the gate shaft 19 for changing the setting of the gate 18 in the manner described I provide a handle 30 on one of the projecting ends of the 75 said shaft 19, as shown in Fig. 4.

The means for cooperating with the eccentric shaft 19 for changing the range of the machine are conveniently provided at the end of the shaft 19 remote from the handle 30, as shown, and comprise means for rotating the said shaft 19 intermittently in one direction, involving the use of a one-way toothed clutch 31 that is mounted on the projecting end portion 32 of the said shaft 80 85 19, and supported by a housing 33.

Incorporated with the clutch structure 31 is a spring 34 that tends to hold the clutch members in cooperating position and is adapted to yield to permit changing the 90 clutch members to a new position, as is common, the said spring 34 being positioned between a collar 35 that is fixed on the extreme shaft end and the part 36 that is slidably mounted on the projecting end portion 32 of the shaft 19 and serves as the moving member of the clutch 31. The part 37 of the clutch 31 is fixedly secured to the shaft 19, and the opposed faces of the parts 36 and 37 are provided with the teeth 38, as shown 95 in Fig. 4, that are adapted for effecting one-way rotation of the shaft 19.

By sliding the part 36 outwardly along the shaft in opposition to the spring 34, to the extent of the depth of the teeth 38, or, in other words, disengaging the clutch members 36 and 37, the clutch would be rendered inoperative, the effect being that notwithstanding continued rotation of the moving part 36 the shaft 19 would not be rotated, and means are provided for permitting of setting the clutch part 36 in such outward, disengaging position in the form of the small swinging arm 39 pivoted to the casing 33, and resting normally on the periphery of the clutch part 36, as shown in 100 Figs. 6 and 7. The clutch part 36 is provided with a radial groove 40 in the periphery that is normally housed within the bearing 41 for the clutch part 36 that is provided 105 in the outer side wall portion 42 of the casing 33 and is adapted to register with the arm 39 when the part 36 is pulled outwardly and receive the said arm 39 so as to prevent 110 return movement of the clutch part 36.

For driving the sliding clutch member 36 and thereby rotating the shaft 19 when the teeth 38 are in position of engagement the said clutch member 36 is provided intermediate the groove 40 and the teeth 38 with an 115 120 125 130

integral gear 43 that is adapted to cooperate with the rack 44 that is provided on the upper end portion of the rod 45 and which extends generally in the vertical direction 5 through the casing 33.

The rod 45 has a limited upward and downward movement and effects a correspondingly limited rotative to and fro movement of the clutch part 36, and the latter 10 drives the shaft 19 one way only by reason of the form of the teeth 38, which, as has been mentioned, are adapted for driving one way only.

For reciprocating the rod 45 the lower end 15 thereof is connected to the upper end of a bracket arm 46 that has at its lower end a hub portion 47 that is operatively mounted on a crank-pin 48 that is provided on a relatively diminutive off-set plate 49 that is 20 mounted in any suitable manner on the opposed end face of the main shaft 17.

As described, means are provided for imparting a positive rotative movement of the gate shaft 19 in one direction only to 25 correspond to each rotation of the main shaft 17, and the extent of such movement is determined by the details and dimensions of the intermediate connecting parts. Also, there is one complete, periodic movement of 30 the gate upward and downward corresponding to each such rotation of the main shaft 17.

Cutting of the sheet metal is effected by the downward movement of the gate.

35 Whether or not there will be such cutting in a given case depends upon the particular setting of the gate 18 that is effected through the medium of the crank-pin 48.

I find it convenient to construct and arrange 40 the parts so that the cutting of the metal by the blades 11 and 12 will be effected at alternate downward movements of the gate 18, corresponding to every other rotation of the main shaft 17. With this arrangement 45 of the parts, means are provided through the arm 39 and the groove 40 for setting the machine by a proper manipulation of the arm 39 so as to cut off the metal into lengths of either one certain dimension or double 50 the said dimension.

The shorter lengths will be cut when the clutch 31 is inoperative, a condition which prevails when the short arm 39 is engaged with the groove 40, as has been described.

55 When the said short arm 39 is released from the groove 40 the clutch 31 is operative, with the result that, for the particular arrangement and adjustment mentioned, for each revolution of the crank-pin 48 that gate shaft 19 will be rotated one-half of a complete revolution, and cutting will be effected only at alternate movements of the gate, as mentioned.

By changing the throw of the crank-pin 60 48 the relation of the rotation of the gate

shaft 19 to the rotation of the main shaft 17 can be changed, so that other than the double relation of the different lengths of stock to be cut can be obtained.

The main shaft 17 may also be termed the 70 bull-gear shaft because the bull-gear 50 is mounted thereon, being a relatively large gear that is driven through the medium of the intermediate gearing that serves to connect the mechanism driven by the said main 75 shaft or bull-gear shaft 17 with the motor 16. Such intermediate gearing in the present instance is arranged to provide a choice of two speeds, as shown in Fig. 2, the change from one to the other being effected by 80 means of the clutch 51 provided on the clutch-shaft 52, and which may be shifted from one side to the other to make the desired connection.

One end of the clutch-shaft 52 overhangs 85 the frame 10 and on the overhanging portion is mounted the relatively large gear 53 that is driven directly by the gear 54 that is mounted on the shaft of the motor 16.

The body portion of the clutch-shaft 52 90 extends across the frame structure 10 and the clutch 51 is mounted adjacent the middle of the said body portion and the said body portion is connected to the adjacent countershaft 55 by two sets of gears, as 95 shown, one on each side of the clutch 51, comprising the gearing 56 between the clutch 51 and the gear 53 and the gearing 57 on the other side of the clutch 51. The gearing 56 is composed of a smaller driving gear 100 and a larger driven gear than the gearing 57 and therefore operates for effecting a relatively slower rate of rotation of the countershaft 55 than the gearing 57.

The gearing interconnecting the counter-shaft 55 and the bull-gear shaft 17 is designated generally by the character 58.

The bull-gear shaft 17 extends through the frame 10, being supported in suitable bearings 59, as shown in Fig. 4; has at one 110 end the off-set disk 49 already described, that serves as a diminutive crank-disk; and has at the other end a crank-disk 60, on a portion of the shaft 17 that overhangs the frame 10, that serves as the driving means 115 for the feed rolls 13 and 14 and the straightening roll structure 15 through the medium of the crank-pin 61 and the connecting rod 62.

The crank-pin 61 is part of a bracket device 63 that is a sliding fit in a diametral 120 T-shaped slot 64 provided in the outer face of the crank-disk 60 and has screw-threaded engagement with an adjusting screw 65 that is housed in the said slot 64.

In Fig. 5 is shown a key structure 66 that 125 is removably engaged with the adjusting screw 65 and is used for setting the said screw 65.

The connecting rod 62 extends generally rearwardly from the crank-pin 61 and has 130

the rear end operatively connected to an elongated, horizontally directed rack 67 through the medium of the bracket 68.

The rack 67 is slidably supported by the frame 10, as shown in Fig. 8, and has teeth 69 on the upper face that cooperate with a gear 70 that is part of a one-way clutch structure 71 that is mounted on the shaft 72, which serves as the feed roll driving shaft.

The clutch structure 71 is an adaptation of the roller clutch of well known form, shown in some detail in Figs. 9 and 10.

As shown, there are four recesses 73 distributed around the periphery of the part 75, which is the inner part of the clutch device proper that cooperate with the opposed enclosing wall 76 of the outer part 77 to form generally V-shaped housings for the roller 78 that is housed in each of the said recesses, and which are backed by spring plungers 79 that tend to force the rollers 78 into the narrow end portion of the housing. Thus the rollers 78 are positioned so that they will be actuated to effect a wedging and binding together of the two parts of the clutch for movement in one direction and will be released and permit of relatively free movement of the parts in the reverse direction.

Thus through the medium of the clutch 71 means are provided for positively driving the feed roll driving shaft 72 in one direction and in cooperation with such driving means there is provided a friction device for preventing reverse movement of the said shaft 72 in the form of a drum 80, Fig. 1, mounted on the shaft 72 and an adjustable friction arm 81 for cooperating therewith. The said friction arm 81 is secured by one end to the frame 10 by means of the screw 82, extends across the drum 80, and at the other end is engaged with an adjusting screw 83 that operates to control the amount of pressure involved in the frictional engagement of the arm and the drum.

The driving gear 84 that is mounted on the shaft 72 I prefer to operatively connect with the said shaft through the medium of a safety friction clutch 85 of any proper form that is adapted to yield under abnormal conditions and thereby prevent rupture of the mechanism.

The driving gear 84 meshes with the gear 85 that is mounted on the gear countershaft 86 through the clutch 87, as shown in Fig. 3, which permits of connecting and disconnecting the feed rollers and the straightening rollers, which rollers are connected to the countershaft 86 by a set of gears that is designated generally by the character 89.

The table 88 shown at the rear end portion of the upper part of the structure shows the elevation at which the sheet metal is delivered to the machine.

The metal is passed between the straightening roller device 15, consisting, as shown, of a set of five rollers, and is entered between the two feed rollers 13 and 14, positioned one above the other.

In use, the feed rollers serve to draw the sheet metal through the straightening device 15 and deliver the same to the cutters.

I claim as my invention:—

1. A cutting-off machine for sheet metal comprising a frame, feed rolls and a cutter-gate supported by the said frame, a bull-gear shaft and a counter-shaft supported by the said frame, mechanism interconnecting the said bull-gear shaft and gate for effecting a reciprocating movement of said gate, gearing interconnecting said counter-shaft and rolls, means for driving said countershaft from said bull-gear shaft comprising a one-way clutch, and retarding means on the said countershaft, said retarding means operating in opposition to said driving means under driving conditions and serving to check reverse movement of the countershaft under non-driving conditions.

2. A cutting-off machine for sheet metal as described in claim 1, a sheet metal straightening device positioned in cooperative relation to said feed rolls.

3. A cutting-off machine as described in claim 1 and auxiliary means for co-operating with the moving means interconnecting the said shaft and gate for changing the operative relation of the said shaft and gate.

4. A power driven cutting-off machine for sheet metal comprising a cutter-gate supporting a cutter and having a reciprocating movement, feed rolls having intermittent rotative movement, and common driving means for said gate and rolls, and the supporting means for the cutter being operatively connected to said driving means so that under operating conditions the position of the cutter relatively to the gate will be varied within prescribed limits.

5. In a cutting-off machine for sheet metal, a cutter supported by a cutter-gate, feed rolls for feeding sheet metal to the said cutter, a shaft operatively connected to the said rolls, retarding means for checking rotation of the said shaft, driving means for driving the said shaft, and a one-way clutch intermediate the said driving means and shaft.

6. In a cutting-off machine for sheet metal, a cutter supporting gate adapted for reciprocating movement, connecting-rod mechanism for operating the said gate, means interconnecting the said mechanism and gate comprising a gate shaft, and the part of the said gate shaft connected to the mechanism being in eccentric relation to the part thereof connected to the gate, whereby the relative longitudinal relation can be changed by rotating the gate shaft.

7. In a cutting-off machine for sheet metal, feeding and cutting mechanism for intermittently feeding and cutting sheet metal and having a gate for supporting a cutter-blade, a main eccentric device for driving the said gate, and a second eccentric structure for positioning the said gate relatively to the said main eccentric device.
8. In combination in a cutting-off machine for sheet metal, a frame, a driving shaft, a gate supported by the said frame, guided for reciprocating movement, and positioned above the said shaft, a pair of eccentrics on the said shaft, a pair of connecting rods operatively connected by their lower ends with the said eccentrics and operatively connected by their upper ends with said gate, and an auxiliary shaft serving as means for interconnecting said rods and gate, said rods and gate having bearings for cooperating each 15 with a part of said auxiliary shaft.

KARL WILLIAM HALLDEN.
